UNITED STATES PATENT OFFICE

153,251

DESIGN FOR A RUG

Lucien Biva, Catskill, N. Y., assignor to E. F. Timme & Son, New York, N. Y., a limited partnership

Application December 16, 1947, Serial No. 143,170

Term of patent 7 years

(Cl. D92—21)

To all whom it may concern:

Be it known that I, Lucien Biva, a citizen of the United States of America, and a resident of Catskill, Greene County, and State of New York, have invented a new, original, and ornamental Design for Rug, of which the following is a specification, reference being had to the accompanying drawing, forming part thereof, in which—

The figure is a plan view of a rug showing my new design.

I claim:

The ornamental design for a rug, as shown.
LUCIEN BIVA.
